UNITED STATES PATENT OFFICE.

GEORGE A. FULLERTON, OF BOSTON, MASSACHUSETTS, ASSIGNOR OF TWO-THIRDS TO WILLIAM F. DUNCAN, OF NEW YORK, N. Y., AND GEORGE H. P. FLAGG, OF BOSTON, MASSACHUSETTS.

BOTTLE-STOPPER.

SPECIFICATION forming part of Letters Patent No. 373,973, dated November 29, 1887.

Application filed May 12, 1887. Serial No. 237,968. (No model.)

To all whom it may concern:

Be it known that I, GEORGE A. FULLERTON, of Boston, in the county of Suffolk and State of Massachusetts, have invented a new and useful Improvement in Combined Bottles and Stoppers, of which the following is a specification, reference being had to the accompanying drawings, in which—

Figure 1 is an elevation of my combined bottle and stopper with the stopper in its highest position. Fig. 2 is a view of my combined bottle and stopper with the stopper forced home. Fig. 3 is a longitudinal section of the same. Figs. 4 and 5 are views of the band, and Fig. 6 is a side view of the stopper and its bail detached.

In the drawings, A is a bottle whose neck a has two grooves, a', and shoulders a³.

The stopper B is secured to a bail, B'.

D is a strip of sheet metal, perforated, as shown in Fig. 4, and forming the band. (Shown detached in Fig. 5.)

The bail B' is a malleable casting, and is so shaped that its ends may be sprung apart sufficiently far to allow them to be passed over the rim of the bottle and snapped into the holes in the band D and into the grooves a'.

The main advantage of my device is its cheapness of construction and the ease of applying it to the bottle, and detaching it and reapplying it when the stopper B requires removal, for although I have shown the stopper B as of rubber, it is for some uses made of cork and requires renewal from time to time.

In applying my device, the band D is first placed around the neck of the bottle, with its end holes in line, and the bail B' is then spread (by pliers or otherwise) so that its inwardly-turned ends will snap into place—that is, through the holes in band D and into the grooves a'. This is done, preferably, when the band D, stopper B, and bail occupy the position shown in Fig. 1. The bottle is then ready to be filled, and when filled the stopper B is forced home and the bail B turned until its inwardly-turned ends engage the shoulders a³, as in other devices of this class.

I am aware that swing-stoppers are old, and do not broadly claim a stopper held to a bottle by a bail and grooves in the neck of the bottle, but limit my claim to the novel features of my construction by means of which I am enabled to produce a swing-stopper far cheaper and more readily applied than any heretofore known and yet equal to any now in the market.

When the cork stopper is to be replaced, the bail B' is sprung open far enough to allow it to be removed from the bottle. The riveted end of the cork spindle is cut off with cutting-nippers, the old cork stopper and its spindle removed, and a new cork stopper and spindle put in its place, the upper end of the spindle being riveted to connect it with the bail. The bail is then sprung open again and allowed to snap back into place on the bottle.

I am aware of Patents No. 231,451 to Schulz, August 24, 1880, No. 266,727 to Schulz, October 31, 1882, and No. 353,069 to Judd, November 23, 1886, and disclaim all that is shown in them. My invention differs radically from the invention set forth in these patents, because my band D is made of a strip whose ends are lapped and perforated to receive one of the inwardly-turned ends of my bail, whereby the band is kept in hoop form, the inwardly-turned end of my bail being in another perforation in band D. By this construction my band, stopper, and bail are secured to the bottle with an economy of labor, and are readily removed from the bottle when necessary, as is frequently the case.

In Schulz's Patent No. 231,451 the band does not encircle the neck of the bottle, and is tied in place by means of a string or wire, (marked h in the patent.) Schulz's Patent No. 266,727 and Judd's Patent No. 353,069 neither show nor suggest a band formed by lapping the perforated ends of the piece of which the band is formed, and the band cannot be removed from the neck of the bottle or jar without being cut or broken, or else without breaking the bottle or jar.

What I claim is—
Bottle A, having grooves a' and shoulders a³,

in combination with stopper B, bail B', having inwardly-turned ends, and a band, D, the ends of which are perforated and lapped to receive one of the inwardly-turned ends of bail B', whose other inwardly-turned end is through another perforation in band D, the bail in place having its inwardly-turned ends

extending through the perforation in band D into the grooves a' , substantially as and for the purpose set forth.

GEORGE A. FULLERTON.
